METHOD OF DIE-FORMING PARTS

George Albert Lyon, Detroit, Mich.

Application June 4, 1936, Serial No. 83,434

8 Claims. (Cl. 113—116)

This invention relates to improvements in a method of blanking or die-forming parts, the invention being highly desirable for use in connection with the forming of automotive vehicle parts, such as a tire cover part, a wheel disk part, a hub cap part and the like.

In the making of ornamental wheel disk constructions, hub caps and similar wheel-covering devices, a portion in simulation of a hub cap is usually formed in the shape of a raised crown embodying an undercut annular indentation or groove, the minimum diameter of which is less than the maximum diameter of the crown portion. In most instances, it has been the custom to spin such a groove formation, and this spinning operation is objectionably difficult and expensive, and in addition requires a relatively light grade of metal to perform the operation with sufficient economy to render it practical. Also the spinning operation has to be employed after the parts have been blanked or stamped with suitable die mechanism, thereby requiring an extra and expensive operation.

The present invention contemplates the method of forming an undercut indentation or recess in an ornamental wheel disk, hub cap or similar wheel-covering element, wherein the spinning operation is eliminated.

Another object of the invention is the provision of a method of forming an undercut indentation or recess in an ornamental wheel covering solely by the use of die mechanism.

Still another object of the invention is the provision of a method of forming a wheel covering with an indented or undercut formation out of relatively heavy or sturdy stock, such, for example, as stainless steel.

It is also a feature of this invention to provide a method of making an automobile wheel covering including the steps of first shaping the disk into a predetermined shape consisting of a crown hub part, and then applying a pressure to the crown part so that the skirt portion thereof is forced to collapse inwardly as a result of the predetermined shape given the wall thereof.

Also an aim of this invention is the provision of a method of forming a wheel disk or similar covering element out of a single blank of stock, the forming operation resulting in a wheel disk or similar element ready for attachment to the vehicle with no other parts united thereto.

In accordance with the general features of this invention, there is provided a method of die-forming a hub cap, wheel disk or similar covering element. First, a blank of material is preformed

with a raised crown portion, the skirt of which is given a predetermined shape. By suitable die mechanism, the blank is again compressed in a manner to retain the shape of the crown portion and also the shape of the disk outside the crown portion, the movement of the die members towards each other resulting in a deflection of the skirt inwardly as a result of the predetermined shape given the skirt, thus providing an undercut indentation or groove in the finished article.

Other objects and features of this invention will more fully appear from the disclosures hereinafter, taken in conjunction with the accompanying drawings, in which:

Figure 1 is a fragmentary, vertical sectional view, with parts in elevation, of apparatus embodying principles of the present invention, showing the same in an initial stage of operation;

Figure 2 is an enlarged showing of the structure seen in the left-hand portion of Figure 1;

Figure 3 is an enlarged fragmentary showing of the structure of Figure 1 in a more advanced stage of operation; and

Figure 4 is a fragmentary, vertical sectional view, with parts in elevation, illustrating apparatus for forming a wheel cover element of slightly different form showing the same in an initial stage of operation.

As shown on the drawings:

For the purposes of illustration, the structures selected to be die-formed by the method embodied in this invention is shown in the form of an ornamental wheel disk of a character designed to cover substantially the entire outer side surface of a vehicle wheel inside the rim. The disk illustrated in Figures 1 to 3, inclusive, is of that type with which a separate hub cap is not utilized, the disk having a central formation in simulation of a hub cap. Of course, the disk may be provided with any desirable contour, depending upon the particular form deemed most desirable for a vehicle to enhance the appearance of the vehicle.

In the present instance, the disk, generally indicated by numeral 1, has been preformed to the shape seen in Figures 1 and 2, by any suitable mechanism, preferably die-forming means. The preformed shape of the disk 1 includes a central dome portion 2 defined by an annular rib 3 terminating in an outwardly sloping skirt portion 4 ending in a relatively deep annular rib 5 which defines the inner portion of an annular skirt 6 in the crown portion of the disk. An outer annular part 7, which may be given substantially any desirable shape for overlying a particular outer part of the wheel, connects the skirt 6 with

the trim 8, which is the part removed from the blank after the disk has been completely formed. On the other hand, this part 8 may be shaped so as to hold a rim-engaging member, if so desired.

An important feature of the present invention is the shape of the preformed part 6. With reference to Figure 2, it will be seen that this part is arcuate in cross-section, and where this part 10 joins the portion 7, substantially a groove 9 is formed, with the outer wall of the part 6 just above the groove 9 substantially straight for a short distance. Of course, details in such configuration may be varied, but the illustrated 15 showing is a satisfactory formation for the purposes intended, and is herein set forth as a specific example. With such a construction, when pressure is applied to the dome-shaped part of the disk, with the annular part 7 held firmly in 20 position, the skirt 6 will curl inwardly in the region of the groove 9 due to the preformed shape of this skirt.

The apparatus for forming the disk 1, as illustrated substantially diagrammatically in the 25 drawings, includes in general a die block, generally indicated by numeral 10, and a punch die or the equivalent, generally indicated by numeral 11. By any suitable means, such as a punch press, for example, these respective die parts 10 30 and 11 may be brought together in a well-known manner. It is preferable, however, that the die block 10 be held in fixed position, and the punch or top die 11 be moved relatively thereto.

The lower die part includes an upstanding die 35 ring 12 defining an inner hollow or cavity for the reception of a reciprocable die pad 13. This pad is normally urged outwardly relative to the ring 12 by any suitable pressure means, such as one or more springs 13a positioned in confronting 40 cavities in the pad 13 and die part 10. The outward movement of the pad is limited by one or more pins or studs 14 fixed in the ring die 12 each with its free end projecting into a notch or recess 14a in the pad.

45 As indicated at 15, the upper face of the die ring 12 is shaped to intimately fit the underface of the part 7 of the disk. The outer face of the pad 13 is shaped to intimately fit the inner face of the dome part of the disk 1 out to and including the upper part of the skirt 6, as clearly seen in Figure 1.

The upper or punch die 11 includes a base portion 16 and an integral central projecting portion 17 faced to intimately overlie the crown part of the disk. This facing is such as to preferably intimately contact the outer surface of the disk including the upper portion of the skirt 6, the die part terminating in an intermediate portion of the skirt, as indicated at 18 in Figure 2, but extending radially outwardly beyond the pad 13. Spaced from the part 17, the base portion 16 is provided with an integral annular depending flange 19 defining an annular recess 20 between itself and the part 17. In this recess, an annular 65 die holding element 21 is slidably mounted and held in position by the engagement of a plurality of pins 22 in a like number of recesses 23.

The pins 22 are fixedly positioned in the depending flange 19, and the recesses 23 occur at 70 like intervals in the die holding part 21, whereby the reciprocal movement of this die part 21 is limited in each direction. A plurality of springs 24, suitably seated in recesses in the base portion 16 and reciprocal die part 21, normally tend to 75 urge this die part outwardly beyond the central

part 17. The reciprocal die part 21 is provided with an annular projection 25, the face of which is shaped complementally to the face 15 on the die block 10, so that the portion 7 of the disk may be firmly and intimately clamped between the two die parts.

With reference to Figure 2, it will be seen that the holding die part 21 is preferably provided with an outwardly inclined or tapered inner wall 26 adjacent the skirt 6 of the disk. This wall 26, while outwardly inclined with respect to the axis of the punch die, is preferably curved so as to be slightly convex, as seen best in Figure 2. It will be understood that the wall portion 26 may be slightly varied in shape consistent with the point at which it is deemed best to have the skirt 6 of the disk contact the same, but it is to be noted that this wall need not of necessity be more than slightly out of alignment from the vertical wall portion thereabove.

After the disk has been preformed in the manner above described and placed between the die members 10 and 11, with the portion 7 of the disk held firmly in position between the face 15 of the die 10 and the part 25 of the reciprocal die part 21, the die members 10 and 11 are brought together. In this movement, the projecting portion 17 and the annular flange 19 of the upper die member move relatively to the die part 21, and the pad 13 of the lower die is moved against the action of the pressure means 13a relatively to the ring die part 12. The original shape of the crown part of the disk is maintained by the part 17 and the pad 13. Due to the previous formation of the skirt 6, this skirt must give and 35 will curve inwardly to form an undercut portion 27, as seen in Figure 3.

When the dies are compressed, the metal of the skirt 6 is urged at an angle against the wall 26, aiding in the collapsing of the skirt. The 40 part 27 provides an inwardly extending annular flange engageable in a snap-on manner by spring-retaining means carried by a vehicle wheel to hold the disk in place upon the wheel. Thus, it will be seen that no extra parts need be 45 added to the disk, but that the disk may be made out of a single piece of material, die-formed with an undercut groove on its exterior side and an inwardly extending flange on its interior. Further, the disk may be formed of relatively heavy 50 metal of the character of stainless steel, if so desired, and no spinning operations are necessary. In this instance, the part 27 is of relatively small radius, with a relatively sharp curve, and is provided by a simple die-forming operation in an 55 extremely economical manner.

With the disk structure above described, the collapse must occur in the skirt 6 of the disk when the die members are brought together. The extent of the collapse or, in other words, the 60 depth of the part 27, may be regulated very effectively by the distance which the upper die member is permitted to move so that the concavo-convex ridge or flange part 27 may be varied in depth and curvature over a considerable extent 65 merely by exercising proper control over the movement of the die mechanism.

In Figure 4, I have illustrated mechanism and indicated the method of forming a similar undercut portion in the skirt of a disk having a 70 relatively smooth dome-shaped portion. The upper die mechanism is the same as that previously described, with the exception that the base 16 is provided with an extension 17a shaped to overlie a smooth dome portion of the disk; 75

i. e., the disk is not provided with the ribs 3 and 5 and the skirt portion 4. In this instance, the disk to be formed includes a central smooth dome 28 joined to a skirt 29 by a relatively smooth curvature 30. The skirt 29 has a portion extending substantially vertically and terminates in a curvature 31 connecting the skirt with an outer flange portion 32 of the same nature as the aforesaid annular part 7, which flange portion terminates in a trim 33 or a part that might subsequently be formed to hold a rim-engaging element. The curvature 30 and the curvature 31 both adapt the skirt so that it will collapse inwardly when subjected to axial pressure by the die mechanism.

The lower die, in this instance, does not need a pressure pad, and this die includes a block 34 having an outer annular portion shaped complementally to the part 25 of the upper die so as to intimately receive the underface of the skirt or annular part 32 of the disk. Inside this part, the die may have a substantially flat surface, as indicated at 35, or, if so desired, the die may be hollowed out to decrease its weight. Due to the fact that the disk has a relatively smooth curvature in the dome-part thereof, it is not necessary to have the underface of this part engaged by a die part, since collapsing will occur in the skirt 29, and the dome part will retain its shape without means in engagement with the undersurface thereof. In the previously described form, the disk was provided with indented parts, such as 4, defined by annular ribs in the disk structure, and to maintain that portion of the disk 1 in its given shape, it is deemed preferable to use the pad 13. However, with the smooth and even dome shape illustrated in Figure 4, the pressure upon the upper face of the disk is transferred to the skirt 29, and when the die mechanism is operated to provide axial pressure upon the disk, the skirt will collapse, as indicated by the dotted lines, to form an inwardly extending flange part 36 defined by an undercut groove on the external surface of the disk. As before, the depth of the part 36 is preferably determined by the relative movements of the die members.

From the foregoing, it is apparent that I have provided a novel method for die-forming a metallic part, the invention being highly desirable for the formation of hub caps, wheel disks and similar wheel-covering devices, the apparatus shown and the practice of the method taught herein resulting in a very economical manufacture of such devices from either light or relatively heavy stock, eliminating costly and expensive operations heretofore required.

I am aware that many changes may be made and numerous details of construction may be varied through a wide range without departing from the principles of this invention, and I, therefore, do not purpose limiting the patent granted hereon otherwise than is necessitated by the prior art.

I claim as my invention:

1. The method of forming an undercut indentation in a crown-like part comprising a top portion, an outer portion, and an annular side wall connecting said portions and which side wall extends abruptly upwardly from said outer portion and then merges with said top portion, which includes: subjecting said part to an endwise pressure while holding said outer portion and to compel the upper portion of said side wall to ride along a generally frusto-conical guiding surface whose greatest diameter is adjacent said outer

portion, while supporting the lower end of said side wall on an abutment surface, thereby to compel a portion of the material in said side wall to progressively move along the abutment surface and form an undercut indentation therein 5 adjacent the abutment surface.

2. The method of forming an undercut indentation in a circular member having a crown-like top portion, an outer portion, and an upstanding side wall connecting said portions, which includes: holding said outer portion against movement and subjecting said crown-like top portion to endwise pressure to force said side wall against an abutment surface adjacent said outer portion, and positioning a guiding surface 10 around said side wall for restraining outward collapse of said side wall, said guiding surface and said wall being provided with a predetermined shape with respect to each other such that their opposed faces adjacent said outer portion 15 flare slightly away from each other.

3. The method of forming an undercut indentation in a circular member having a crown-like top portion, an outer portion, and an upstanding side wall connecting said portions, which includes: holding said outer portion against movement and subjecting said crown-like top portion to endwise pressure to force said side wall against an abutment surface adjacent said outer portion, and positioning a guiding surface around said 20 side wall for restraining outward collapse of said side wall, thereby to collapse said side wall inwardly from the held outer portion to form an undercut indentation in the wall between the top and outer portions.

4. The method of forming an annular intermediate fold in a sheet metal member, which includes holding a marginal portion of the member while feeding an intermediate annular portion of the metal member along a sleeve-like guiding surface against an abutment surface, said annular portion of said member being progressively forced out along said abutment surface away from said guiding surface, thereby forming an intermediate annular fold in said member.

5. The method of forming an annular intermediate fold in a sheet metal member, which includes holding a marginal portion of the member while feeding an intermediate annular portion of the metal member along a sleeve-like guiding surface against an abutment surface, the sleeve-like guiding surface being flared away from said annular portion adjacent said marginal portion, said annular portion of said member being progressively forced out along said abutment surface away from said guiding surface, thereby forming an intermediate annular fold in said member.

6. The method of forming an annular intermediate fold in a sheet metal member, which includes holding a marginal portion of the member while feeding an intermediate annular portion of the metal member along a sleeve-like guiding surface against an abutment surface, the sleeve-like guiding surface and the intermediate annular portion of said member being flared away from each other adjacent said marginal portion, and said abutment surface being inclined with respect to said guiding surface, said annular portion of said member being progressively forced out along said abutment surface away from said guiding surface, thereby forming an intermediate annular fold in said member.

7. The method of forming an annular intermediate fold in a sheet metal member which in-

cludes holding a marginal portion of the member while moving an intermediate annular portion of the member at an angle toward a guiding surface and against an abutment surface inclined to the guiding surface to compel the moving annular portion of the metal member to progressively move along the abutment surface, thereby forming an annular fold in said member.

8. The method of forming an intermediate fold in a circular member having a central part, a

marginal part, and an intermediate upstanding annular wall connecting said parts, which includes: holding the marginal portion of said member and forcing the wall portion vertically along a guiding surface toward an abutment surface, thereby compelling the wall portion to move progressively along the abutment surface and form a fold in said member.

GEORGE ALBERT LYON. 10
